UNITED STATES PATENT OFFICE.

LESLIE MORRIS SOBER AND ELMER ELLSWORTH BROWN, OF OKLAHOMA,
OKLAHOMA TERRITORY; SAID BROWN ASSIGNOR TO JAMES L. McCUNE,
OF OKLAHOMA, OKLAHOMA TERRITORY.

TIME CHECK OR RECORDER.

No. 820,894.

Specification of Letters Patent.

Patented May 15, 1906.

Application filed June 12, 1905. Serial No. 264,855.

To all whom it may concern.

Be it known that we, LESLIE MORRIS SOBER and ELMER ELLSWORTH BROWN, residing at Oklahoma, in the county of Oklahoma, in the Territory of Oklahoma, have invented 5 certain new and useful Improvements in Time Checks or Recorders, of which the following is a specification.

Our invention relates to certain new and 10 useful improvements in workmens' time-recorders for recording various data relative to the time of work of workmen, &c., and it particularly relates to the class of time-recorders in which the operator is required to sign his 15 name or make other identification-marks on a recording sheet or strip each time he registers, which type of machines is commonly known as "autograph" machines. Machines of this type commonly embrace a clock mechanism, a printing mechanism controlled or 20 operated by such mechanism, a recording sheet or strip, and mechanism for moving the sheet or strip to bring the latter into position for signature either at or immediately before 25 or after the time is printed thereon.

This invention seeks to provide a machine of the foregoing class in which means are provided for quickly and effectively making the proper record on the strip or sheet, moving 30 the said sheet along after each entry to expose a new surface for the succeeding entry, and in which means are also provided for perforating the sheet or strip between each entry, so that each entry may be separated 35 from the other and filed away for proper reference.

Our invention also provides a recording mechanism which automatically registers the time of making the entry, in which the operating mechanism therefor is beyond the access of the person making the entry, and in which each entry is made upon a strip or scroll, which is so arranged as to be automatically wound up step by step after each 45 entry to carry the entry beyond the reach of the operator to prevent fraudulent entries being made, and when an entry is once made to prevent its being tampered with.

In our invention means are also provided 50 whereby the entry, immediately after it has been moved beyond the control of the operator, is exposed to the view under a trans-

parent plate, so that the record made can be readily observed by the operator and compared with the clock-reading to detect any 55 errors should the mechanism get out of order.

This invention also seeks to provide a mechanism of the character stated in which the time-wheels are operated by a clock mechanism separate and distinct from and 60 having no relative connection with the mechanism for pressing the paper against the wheels to stamp the day and time on the paper.

With other objects in view than have been 65 heretofore enumerated our invention consists in certain novel construction, combination, and arrangement of parts, all of which will be first described in detail, and then specifically pointed out in the appended claims, 70 reference being had to the accompanying drawings, in which—

Figure 1 is a perspective view of our invention. Fig. 2 is a top plan view thereof with the lid open. Fig. 3 is a side elevation and 75 part longitudinal section thereof. Fig. 4 is a top plan view of our invention, parts being broken away and the lid open. Fig. 5 is a cross-section on the line 5 5 of Fig. 3. Fig. 6 is an enlarged detail end view of the time- 80 stamp wheels and their operating mechanism. Fig. 7 is a detail side elevation of the parts shown in Fig. 6. Fig. 8 is a detail view of the imperforator-plates. Fig. 9 is a detail view of the dial and pointer for the month-wheel. Fig. 10 is a detail view of a modification hereinafter specifically referred to. Fig. 11 is a cross-section on the line 11 11 of Fig. 3. Fig. 12 is a section on the line 12 12 of Fig. 2.

Referring now to the accompanying drawings, in which like numerals of reference indicate like parts in all of the figures, it will be seen that 1 designates a casing, comprising the desk portion 1^a and the clock-housing 1^b, in which housing 1^b any suitable clock mechanism 95 2 is disposed.

Mounted for rotation on a shaft 3 within the desk part 1^a of the casing 1 is a set of wheels 4 5 6, one of which, 4, has its periphery 4^a provided with indicating numbers or 100 type designating hours in the day. On each type there are two sets running from "1" to "12," inclusive each, one set being in light-face type to designate the hours from mid-

night to noon, while the other set of numbers is in heavy-face type to designate the hours from noon to midnight.

The second wheel 5 has its periphery 5^a provided with numbers running from "1" to "60," inclusive, to designate minutes in the hour, while the third wheel 6 has its periphery 6^a provided with characters designating days in the month and running from "1" to "31," inclusive.

We preferably arrange the hour and minute wheels 4 and 5 adjacent one another, as shown, while the month-wheel 6 is spaced apart from the wheel 5. Between the wheels 5 and 6 the wheel 5 carries a ratchet 5^b, having peripheral ratchet-teeth 5^c of a number equal to the number on the periphery of the minute-wheel 5—*i. e.*, sixty teeth. At a suitable place the ratchet 5^b has a stud 5^d, which engages a lever 7, fulcrumed at 7^a, which lever 7 carries a pawl 7^b to engage a ratchet 8, secured to the wheel 4, so that when the wheel 5 makes one revolution the wheel 4 will be moved one space forward, it being understood that the ratchet 8 has teeth 8^a equal in number to the numbers on the periphery 4^a of the wheel 4—*i. e.*, twenty-four teeth. As the stud 5^d disengages the lever 7 a spring 7^c returns the lever 7 to its normal position and moves the wheel 4 the required distance.

To prevent the wheels 4 5 6 being turned backward, check-pawl 4^x, 5^x, and 6^x are provided, which pawls 4^x, 5^x, and 6^x are held in engagement with the respective ratchets 8, 5^b, and 9 of the wheels 4 5 6, as shown, the wheel 6 having a ratchet 9 attached thereto, as clearly shown in Fig. 6.

The wheel 6 has a sleeve or hub 10^b, which projects through the wall of the casing and carries a pointer 10^a and a milled turn-head 10^d, whereby the wheel 6 can be turned to set it to bring the proper day-number in alignment, a dial 11 being provided on the casing-wall, upon which are numbers corresponding to those on the wheel 6, and the said dial 11 coöperates with the pointer 10^a, as shown in Fig. 7.

12 designates a rod mounted in bearings 12^a 12^a, which projects between the wheels 5 and 6 and carries a pawl 13, which is held in engagement with the teeth 5^c of the ratchet 5^b. A coil-spring 14, mounted on the rod 12 adjacent one bearing thereof, engages a pin 14^a on the rod 12 to move the rod in one direction to turn the ratchet 5^b, and consequently move the wheel 5, a check-nut 14^b being provided to limit the movement of the rod 12 and adjust the same.

Pivotedly secured to the rod 12 at 15^a is a lever 15, which is fulcrumed at 15^b and carries a friction-roller 15^c at its free end. The lever 15 projects up into the clock-casing 1^b and coöperates with a disk 16 on a shaft 16^a, which disk 16 has a groove 16^b to receive the friction-roller 15^c once in every revolution of

the disk. Motion is imparted to the disk 16 from a shaft 18, driven in any suitable manner by the clock-work motor of the clock mechanism 2 through bevel-pinions 17 17^a, as clearly shown in Fig. 3. The disk 16 and its connection with the clock-motor is such that the disk 16 rotates at a speed of one revolution per minute, so that the friction-roller 15^c enters the groove 16^b once in every minute to release the rod 12 and permit the spring 14 to operate the rod and turn the minute-wheel 5 one space each minute.

20 designates a segmental disk upon whose peripheral segment 20^a a series of indicating-type 20^b is formed, preferably the words "Report" and "Leave," "Return" and "End," each word being spaced from the other a certain number of degrees, so that only one word at a time will be in proper alignment to be impressed upon the paper when the impressor 51 is operated, as will be hereinafter more fully apparent.

The disk-segment 20 is fulcrumed on the shaft 3 and has a radial tailpiece 20^c, to which the end 21^a of a presser-rod 21 is fulcrumed.

The rod 21 is endwise movably held in a bearing 22 and carries a friction-roller 25 at its free end to coöperate with the cam portions 24^a of the keys 24, of which there are a number equal to the number of words on the peripheral segment 20^a. Each key 24 includes a finger-engaging head 24^x outside of the casing, upon which words corresponding to those on the peripheral segment 20^a are formed. Each key 24 also includes a stem 24^y, projected within the casing. As shown in Fig. 5, the stems 24^y are bent, as at 24^z, until the ends are adjacent one another and close together. The stem 24^y of the key 24, upon which the word "Report" is marked, has no cam 24^a, as the segment 20 is normally set with the word "Report" in register with the impressor 51.

The cam 24^a on the "end" key is twice as large as that on the "return-key" and three times as large as that on the "leave-key," so that when the respective keys are depressed the segment 20 will be moved a proper distance to move the proper word on the periphery 20^a of the segment 20 in register.

Spring devices 24^b are mounted on each key 24 to return the keys to their normal elevated position.

26 designates the spool of paper, rotatably mounted in the casing, while 27 designates the bobbin over which the paper is to be wound. The bobbin 27 is mounted on a shaft 28 to turn therewith. 29 designates a ratchet on the shaft 28, with which the spring-pressed pawl 30 on the lever 31 engages. The lever 31 is fulcrumed, as at 32, and has its free end connected to one end of a lever 34 by a link 33. The lever 34 is fulcrumed at 34^a and has its free end 34^b in position to be engaged by

the stems 24^y of the keys 24, a spring 35 being provided to move the lever 34 to its normal position and to rotate the ratchet 29 to wind the paper upon the bobbin 27.

5 36 designates an elastic buffer below the lever 34 to be engaged thereby and when the lever 34 is depressed to take up the impact due to the operation of the keys 24, a similar buffer 37 being provided on the lever end to coöperate with the stems 24^y of the keys 24, as shown.

To return the segmental disk 20 to its normal position after each operation of the machine, we provide a coil-spring 20^e, which is secured to the tailpiece 20^e and to a pillar 20^f on the casing-floor.

15 38 designates an elongated opening in the top of the desk which may be provided with a metallic guard-plate under which a plate 39 is held. The plate 39 is of a length equal to the width of that part of the strip or sheet 26 upon which the writing is to be made. The strip 26 passes under the roller 40 and over 20 41, the plate 39, and peripheral segment 20^a, 25 and wheels 4, 5, and 6, and over the friction-roller 42 onto the bobbin 27, upon which it is adapted to be wound, it being understood the paper is of a sufficient width to cover the plate 39, the segmental disk 20, and the 30 wheels 4, 5, and 6.

Wound upon a bobbin 43, rotatably mounted within the casing, is a carbon-ribbon 44, which passes under friction-rollers 45 and 46 into a housing 47, where it passes over 35 rollers 48 48 and back over the, and adjacent the, strip 26, the ribbon being of a width equal to the wheels 20, 4, 5, and 6 and being held out of direct contact with the strip 26 by rollers 49 49. The ribbon 44 then passes 40 onto a bobbin 50, upon which it is adapted to be wound. The bobbin 50 is mounted to turn with a shaft 50^a, which receives its motion from the shaft 26^x, upon which the spool or bobbin 26^y is mounted, through intermeshing gears 26^z and 50^x on the shafts 26^d and 50^a, respectively.

45 The impressor 51 comprises a stamping-plate 52, disposed in the housing 47 above that portion of the ribbon 44 which is adjacent the strip 26 in alinement with the plate 39 and directly over the wheels 4, 5, and 6 and the segment 20^a. The plate 52 is secured to a rod 53, which is endwise mounted in the bearing 54 on the casing side, and secured to the bearing and to a stop 55 on the rod 53 is a coil-spring 56, which normally holds the rod 53, with the plate 52, just clear of the ribbon 44 and which when the rod 53 is raised and suddenly released causes the 50 stamp-plate 52 to impact on the ribbon and press it and the strip 26 against the wheels 4, 5, and 6 and the segment 20^a to cause the carbon-ribbon to print the time, day, &c., on the strip in a manner presently more fully explained.

The rod 53 has a heel 57, which coöperates with the heel 56^m on the lever 34 in a manner presently more fully understood.

59 designates a lug or stud on the casing-wall which when engaged by the heel 57 moves 70 the rod 53 off the heel 56^m to allow the spring 56 to operate the rod. A flat spring 60 on a pillar 61 engages the lower end of the rod 53 to normally press it against the lug 59, as clearly shown in Fig. 3.

75 62 designates a plate mounted across the strip 26 and above the same, which plate 62 is provided with apertures 62^a to receive and coöperate with points or pins 63^a on a second plate 63, mounted in alinement with the 80 plate 62 below the strip 26. The plate 63, coöperating with the plate 62, serves as a means for perforating the strip between each entry.

85 64 designates a rod mounted in a bearing 65 on the casing-wall, which is rigidly secured at its top end to a plate 63, and at its lower end the rod is secured to a bell-crank lever 66, fulcrumed at 66^a and having its other end connected to the lever 31 through 90 the link 67, as shown, whereby when the key 24 is depressed and the lever 34 rocked the rod 64 is also lowered to withdraw the pin 63^a from the apertures 62^a and from the strip 26, and when the key 24 is released the rod 64 95 will return the pins 63 into the apertures 63^a through the strip 26 and perforate the same.

To aid in moving the rod 64 to its "perforated" position, a coil-spring 68 is mounted on the rod 64 between the bearing 65 and the 100 stop 69 on the rod 64. The lever 66 is bent to draw the rod 64 past the dead-center, thereby holding the perforator-plate 63 down until the movement of the paper is accomplished.

105 The plates 62 and 63, together with their interlocking apertures and pins 62^a 63^a, respectively, serve to hold the paper or strip in place when the roll is taken out to cut off the record end which has been rolled or wound onto the bobbin 27.

In Fig. 10 we have shown a slightly-modified arrangement of the parts to be used in connection with our apparatus when the perforating-plate 63 is not used. By reference 115 to Fig. 10 it will be seen that we fulcrum a plate 70 at one side of the strip 26, as at 71, which plate 70 extends across the strip 26 below the same and in alinement with the plate 62. To hold the paper between the two 120 plates, a coil-spring 72 is connected with a heel 83 of each plate 70, which presses the plate 70 against the paper strip 26 and the fixed plate 62. At its free end the plate 70 has an angled extension 74, provided with a 125 head 75, which is adapted to be engaged by the desk-top when closed to move the plate 70 down in the direction of the arrow in Fig. 10 to release the strip 26 when the desk-lid is closed down, it being understood that as soon 130

as the lid is opened the spring 72 again moves the plate 70 up in the direction opposite to the arrow in Fig. 10 to hold the strip 26 against the plate 62.

5 So far as described the manner in which my invention operates will be best explained as follows:

Operation: Supposing that "Richard Rowe" reports for duty. He stands at the 10 desk and signs the paper or scroll at the one place where it is exposed—*i. e.*, at the aperture on the top of the desk. He then presses the key marked "Report," and the impressor is then brought down upon the carbon-ribbon 15 opposite his signature and upon the time-wheels beneath, which are operated by the ordinary clockwork devices independent of the devices which move the paper. As the 20 impressor is released from the paper the paper is wound upon the bobbin within the desk to a sufficient extent to carry the signature beyond the aperture and under the glass plate and bring the clean surface into alignment with the aperture for the next signature. The signature moves under the glass 25 plate and into the desk and out of the way of tampering. Should "Richard Rowe" forget to press the key, his name remains exposed and the deception or negligence is in 30 full view of the foreman or superintendent. The next clerk must necessarily press the key and impress an improper date opposite "Richard Rowe's" name, date, &c., in case of reporting would be against "Richard 35 Rowe's" interest. In leaving, the last signer might gain some advantage by neglecting to press the key were it not for the fact that his name would be exposed during the entire time that he might gain, thus making 40 discovery of the fraud so easy that the risk of exposure would act as a complete deterrent. As the key is depressed the cam thereon will move the rod which operates the segmental disk to bring the proper type in register with 45 the impressor before the impressor is released to stamp the characters upon the strip, as before explained.

Our invention is particularly adapted for use in public offices—such as post-offices, 50 custom-houses, &c., and all other public and private institutions employing labor and where an exact report of the time devoted to the performing of labor by each individual is necessary. Our invention, again, also can 55 be readily used in many other places wherever and whenever found desirable.

From the foregoing it will be seen that we have provided a very simple, easily, and quickly operated time-recording means which 60 will readily and effectively serve its intended purposes.

From the foregoing, taken in connection with the accompanying drawings, it is thought that the complete construction, operation, and many advantages of our inven-

tion will be readily understood by those skilled in the art to which it appertains.

Having thus described our invention, what we claim, and desire to secure by Letters Patent, is—

1. In a time-check and recording mechanism, a casing having a desk portion, a series of dating-wheels, clock mechanism for setting said wheels, said desk portion of the casing including a removable top having an aperture and a transparent portion, a plate held under said top aperture, means for moving a record-receiving strip over said plate and said wheels, a supplemental segmental wheel having peripheral characters, a carbon-ribbon held over said paper in line with all of said wheels, means for setting said supplemental wheel to bring a predetermined portion of its circumference in line with said plate, means coöperating with said supplemental-wheel-setting means, for pressing the ribbon and the record-receiving strip against the several wheels, and means, co-operating with said supplemental-wheel-setting means and said pressing means, for moving said strip with the record from under the top aperture and under the transparent portion of the top, substantially as shown and described.

2. In a time-check and recording mechanism, a casing having a desk portion, a series of dating-wheels, a clock mechanism for setting said wheels, said desk portion of the casing including a removable top having an aperture and a transparent portion, a plate held under said top aperture, means for moving a record-receiving strip over said plate and said wheels, a supplemental segmental wheel having peripheral characters, a carbon-ribbon held over said paper in line with all of said wheels, means for setting said supplemental wheel to bring a predetermined portion of its circumference in line with said plate, means, coöperating with said supplemental-wheel-setting means and said pressing means for moving said strip with the record from under the top aperture and under the transparent portion of the top, and means for perforating said strip after each record.

3. In a time-check and recording mechanism, a casing having a desk portion, a series of dating-wheels, clock mechanism for setting said wheels, said desk portion of the casing including a removable top having an aperture and a transparent portion, a plate held under said top aperture, means for moving a record-receiving strip over said plate and said wheels, a supplemental segmental wheel having peripheral characters, a carbon-ribbon held over said paper in line with all of said wheels, means for setting said supplemental

wheel to bring a predetermined portion of its circumference in line with said plate, means, coöperating with said supplemental-wheel-setting means, for pressing the ribbon and 5 the record-receiving strip against the several wheels, means coöperating with said supplemental-wheel-setting means and said pressing means, for moving said strip with the record from under the top aperture and under the transparent portion of the top, and 10 means for gripping said strip to hold the same from movement while the recorded portion of the strip is being removed from the casing, substantially as shown and described.

15 4. In an apparatus of the class described, a casing including a desk portion having an apertured lid, a shaft mounted within the casing, a pair of time-wheels mounted on the shaft, means for automatically setting said 20 time-wheels, a supplemental dating-wheel mounted on the shaft and having a hub portion projecting through the casing, a turn-head and a pointer on said hub portion, a scale on the casing for coöperating with said 25 pointer, a spindle within the casing adapted to receive a roll of paper, a second spindle also within the casing and adapted to receive the paper as it is unwound from the first spindle, a writing-plate over which and the time 30 and dating wheels the paper passes, a ribbon held above the paper and the time and dating wheels, means for pressing the ribbon against the paper and the wheels at times to leave a record on the paper, said desk-lid 35 aperture adapted to expose a part of the paper to receive writing thereon, a segmental character-bearing wheel adjacent the time-wheels, said segmental wheel having peripherally-arranged and spaced characters, a 40 plurality of keys, one for each peripheral-wheel character, means coöperating with said keys for setting said peripheral wheels and means operated by said keys for moving said paper and ribbon forward after each entry 45 to remove the recorded portion of the paper from under the desk writing-aperture, substantially as shown and described.

5. In an apparatus of the class described, a casing including a desk portion having an apertured lid, a shaft mounted within the casing, a pair of time-wheels mounted on the shaft, means for automatically setting said 50 time-wheels, a supplemental dating-wheel mounted on the shaft and having a hub portion projecting through the casing, a turn-head and a pointer on said hub portion, a scale on the casing for coöperating with said pointer, a spindle within the casing adapted to receive a roll of paper, a second spindle 55 also within the casing and adapted to receive the paper as it is unwound from the first spindle, a writing-plate over which and the time and dating wheels the paper passes, a ribbon held above the paper and the time and dating 60 wheels, means for pressing the ribbon

against the paper and the wheels at times to leave a record on the paper, said desk-lid aperture adapted to expose a part of the paper to receive writing thereon, a segmental character-bearing wheel adjacent the time-wheels, 70 said segmental wheel having peripherally-arranged and spaced characters, a plurality of keys, one for each peripheral-wheel character, means coöperating with said keys for setting said peripheral wheel means for moving said paper and ribbon forward after each entry to remove the recorded portion of the paper from under the desk writing-aperture, and means controlled by said keys for perforating 75 said paper between the records. 80

6. In a device of the class described, the combination of a paper-ribbon-moving device actuated from the exterior of the casing, a plurality of time-indicating wheels, means for setting said wheels, a segmental character-bearing wheel, having a plurality of peripheral characters, means actuated by the paper-moving-device-actuating means, for setting said segmental wheel, a slotted cover through which the paper is disclosed and 85 means coöperating with said paper-moving mechanism for pressing the paper against the time and segmental wheels, substantially as shown and for the purposes described. 90

7. In an apparatus of the class described, a desk having a lid provided with an elongated aperture and a housing at one end of said aperture, a ribbon - holding bobbin mounted within the desk, guide-rollers in the lid-housing, a ribbon-receiving bobbin within the 100 desk, said ribbon passing over said housing-rolls and onto said receiving-bobbin, a paper-holding bobbin and a paper-receiving bobbin, a writing-plate secured within the desk below the lid-aperture, said paper adapted to pass 105 over said writing-plate, means within the casing for intermittently winding said paper upon said paper-receiving bobbin, a plurality of time-wheels arranged within the casing, below the lid-housing and the paper and ribbon, independent means for automatically setting said time-wheels, a segmental wheel having peripherally-arranged indicating characters, mounted adjacent said time-wheels, means within the casing for setting 110 said segmental wheel, an impresser within the lid-housing above the ribbon, means controlled by the paper-winding means for actuating said impresser, substantially as shown and for the purposes described. 115

8. In an apparatus of the class described, a desk having a lid provided with an elongated aperture and a housing at one end of said aperture, a ribbon - holding bobbin mounted within the desk, guide-rollers in the lid-housing, a ribbon-receiving bobbin within the 120 desk, said ribbon passing over said housing-rolls and onto said receiving-bobbin, a paper-holding bobbin and a paper-receiving bobbin, a writing-plate secured within the desk 125 130

- below the lid-aperture, said paper adapted to pass over said writing-plate, means within the casing for intermittently winding said paper upon said paper-receiving bobbin, a plurality of time-wheels arranged within the casing, below the lid-housing and the paper and ribbon, independent means for automatically setting said time-wheels, a segmental wheel having peripherally-arranged indicating characters, mounted adjacent said time-wheels, means within the casing for setting said segmental wheel, an impressor within the lid-housing above the ribbon, means controlled by the paper-winding mechanism for actuating said impressor, means connected with the paper-winding means for perforating the paper between the records, substantially as shown and described. 75
11. In an apparatus of the class described, a desk having a lid provided with an elongated aperture and a housing at one end of said aperture, a ribbon - holding bobbin mounted within the desk, guide-rollers in the lid-housing, a ribbon - receiving bobbin within the desk, said ribbon passing over rolls and onto said receiving-bobbin, a paper-holding bobbin and a paper-receiving bobbin, a writing-plate secured within the desk below the lid-aperture, said paper adapted to pass over said writing-plate, means within the casing for intermittently winding said paper upon said paper-receiving bobbin, a plurality of time-wheels arranged within the casing, below the lid-housing and the paper and ribbon, independent means for automatically setting said time-wheels, a segmental wheel having peripherally-arranged indicating characters mounted adjacent said time-wheels, means within the casing for setting said segmental wheel, an impressor within the lid-housing above the ribbon, means controlled by the paper-winding mechanism for actuating said impressor, means connected with the paper-winding means for perforating the paper between the records, substantially as shown and described. 80
12. In an apparatus of the class described, a desk having a lid provided with an elongated aperture and a housing at one end of said aperture, a ribbon - holding bobbin mounted within the desk, guide-rollers in the lid-housing, a ribbon-receiving bobbin within the desk, said ribbon passing over said housing-rolls and onto the receiving-bobbin, a paper-holding bobbin and a paper-receiving bobbin, a writing - plate secured within the desk below the lid-aperture, said paper adapted to pass over said writing-plate, means within the casing for intermittently winding said paper upon said paper-receiving bobbin, a plurality of time-wheels arranged within the casing, below the lid-housing and the paper and ribbon, independent means for automatically setting said time-wheels, a segmental wheel having peripherally-arranged indicating characters, mounted adjacent said time-wheels, means within the casing for setting said segmental wheel, an impressor with- 85 90 95 100 105 110 115 120 125 130
13. In an apparatus of the class described, a desk having a lid provided with an elongated aperture and a housing at one end of said aperture, a ribbon - holding bobbin mounted within the desk, guide-rollers in the lid-housing, a ribbon-receiving bobbin within the desk, said ribbon passing over said housing-rolls and onto the receiving-bobbin, a paper-holding bobbin and a paper-receiving bobbin, a writing - plate secured within the desk below the lid-aperture, said paper adapted to pass over said writing-plate, means within the casing for intermittently winding said paper upon said paper-receiving bobbin, a plurality of time-wheels arranged within the casing, below the lid-housing and the paper and ribbon, independent means for automatically setting said time-wheels, a segmental wheel having peripherally-arranged indicating characters, mounted adjacent said time-wheels, means within the casing for setting said segmental wheel, an impressor with- 135
14. In an apparatus of the class described, a desk having a lid provided with an elongated aperture and a housing at one end of said aperture, a ribbon - holding bobbin mounted within the desk, guide-rollers in the lid-housing, a ribbon-receiving bobbin within the desk, said ribbon passing over said housing-rolls and onto the receiving-bobbin, a paper-holding bobbin and a paper-receiving bobbin, a writing - plate secured within the desk below the lid-aperture, said paper adapted to pass over said writing-plate, means within the casing for intermittently winding said paper upon said paper-receiving bobbin, a plurality of time-wheels arranged within the casing, below the lid-housing and the paper and ribbon, independent means for automatically setting said time-wheels, a segmental wheel having peripherally-arranged indicating characters, mounted adjacent said time-wheels, means within the casing for setting said segmental wheel, an impressor with- 140 145 150
15. In an apparatus of the class described, a desk having a lid provided with an elongated aperture and a housing at one end of said aperture, a ribbon - holding bobbin mounted within the desk, guide-rollers in the lid-housing, a ribbon-receiving bobbin within the desk, said ribbon passing over said housing-rolls and onto the receiving-bobbin, a paper-holding bobbin and a paper-receiving bobbin, a writing - plate secured within the desk below the lid-aperture, said paper adapted to pass over said writing-plate, means within the casing for intermittently winding said paper upon said paper-receiving bobbin, a plurality of time-wheels arranged within the casing, below the lid-housing and the paper and ribbon, independent means for automatically setting said time-wheels, a segmental wheel having peripherally-arranged indicating characters, mounted adjacent said time-wheels, means within the casing for setting said segmental wheel, an impressor with- 155 160 165 170 175 180 185 190 195 200

- in the lid-housing above the ribbon, means controlled by the paper-winding mechanism for actuating said impressor, means connected with the paper-winding means for perforating the paper between the records, and means operated from the exterior of the casing for actuating said paper-winding means and said segmental-wheel-setting means, substantially as shown and described.
13. In a mechanism of the character stated, a casing having a lid provided with an elongated aperture, and a transparent portion adjacent thereto, means for moving a paper strip in the casing under the lid-aperture and the transparent portion the strip being adapted to receive a written entry and a printed record thereon, a printing mechanism for making such printed record comprising dating-wheels, mechanism for automatically setting said dating-wheels, a printing-ribbon, means independent of the wheel-setting mechanism for pressing the ribbon against the paper and the wheels to imprint a record on the paper, means for moving said paper after each record to expose the record under the transparent portion of the lid, means controlled by the paper-moving means for moving the ribbon, a segmental wheel arranged adjacent the dating-wheels and having peripherally-arranged characters, means for setting said segmental wheel to its proper position, and a plurality of keys one for each segmental character of the peripheral wheel for actuating said setting means, said paper-moving means and said impressing mechanism substantially as shown and described.
14. In an apparatus of the class described, a casing having a lid provided with an elongated aperture and a transparent portion adjacent thereto, a hood at one end of said elongated aperture, a shaft mounted within said casing, a pair of time-indicating wheels mounted on said shaft, a clock mounted within the casing, gear connections between said clock and said time-indicating wheels for moving the time-indicating wheels in unison with said clock, a third time-indicating wheel mounted adjacent the other time-indicating wheels, means connected with said third time-indicating wheel and extending to without the casing by means of which said wheel can be turned, a pointer on said turning means, a scale-plate on said casing for coöperating with the pointer, a segmental wheel mounted adjacent the first-mentioned time-indicating wheels on said shaft, said segmental wheel having a plurality of peripherally-spaced indicating characters, a writing-plate under the aperture in the casing-lid, a paper-roll holder mounted within the casing and a paper-receiving roll also mounted within the casing, friction-rollers mounted in the casing for receiving said paper, said paper passing over said writing-plate and said wheels, a ratchet-and-pawl de-
- vice for winding up said paper onto the paper-receiving roll, an impressor extended up into the lid-hood and means for operating said ratchet-and-pawl paper-moving means and said impressor, said last-named means including a lever fulcrumed on the casing-bottom, a pitman connected to said segmental wheel, a plurality of keys having cam-surfaces, one key for each peripheral indicating character of the segmental wheel, said keys adapted to coöperate with said pitman whereby when the keys are depressed the pitman will be moved to turn the segmental wheel, said keys also co-

operating with said paper-moving means and said impressor-actuating lever for operating said lever, a ribbon passing over the paper and over said wheels, and in the lid-hood, means for moving said ribbon synchronously with said paper, said ribbon-moving means comprising a gear connection with said paper-moving means, a plate mounted within the casing over said paper, said last-named plate having a plurality of pin-receiving apertures, a perforating-plate

having pins for entering said apertures, said perforating-plate held beneath said apertured plate and said paper, and means connected with the paper-moving means for actuating said perforating-plate, substantially as shown and described. 15
